T. LUND,
PREPARATION OF HEEL BLANKS,
APPLICATION FILED FEB. 12, 1919.

1,401,165.

Patented Dec. 27, 1921.

INVENTOR-
Thomas Lund
By his Attorney
Nelson M. Howard

UNITED STATES PATENT OFFICE.

THOMAS LUND, OF BEVERLY, MASSACHUSETTS, ASSIGNOR TO UNITED SHOE MACHINERY CORPORATION, OF PATERSON, NEW JERSEY, A CORPORATION OF NEW JERSEY.

PREPARATION OF HEEL-BLANKS.

1,401,165.

Specification of Letters Patent. Patented Dec. 27, 1921.

Application filed February 12, 1919. Serial No. 276,572.

To all whom it may concern:

Be it known that I, THOMAS LUND, a citizen of the United States, residing at Beverly, in the county of Essex and State of Massachusetts, have invented certain Improvements in the Preparation of Heel-Blanks, of which the following description, in connection with the accompanying drawings, is a specification, like reference characters on the drawings indicating like parts in the several figures.

This invention relates to the preparation of heel blanks. The satisfactory attachment of a heel to a shoe or a top lift to a heel requires, under most conditions, the application of adhesive between the heel and the heel seat portion of the shoe sole or between the top lift and the heel, as the case may be. This is customarily effected by a daub of liquid glue, applied to one of the parts to be brought into contact, at the time of the attaching operation, either by a hand brush or by an appliance attached to the heelng machine. This necessitates keeping the glue pot and glue in condition for immediate use at all times and is accompanied by a considerable waste of glue and occasional damage to the stock by the misuse of the glue in a fluid condition about the work.

The present invention is directed to the elimination of all liquid glue about the heelng machine by the incorporation in the heel blank, in the course of its manufacture, of an appropriate, dry adhesive which requires only softening, as, for example, by contact with a damp sponge, vapor or heat, to render it effective for producing a close connection between the blank and the part to which it is to be attached by the heelng machine.

In one aspect, the invention accordingly consists in a method of making heel blanks which includes applying and forcing a dry adhesive into that surface of a blank which is to be attached to another part of a shoe. This may advantageously be done at the time of the usual blank compressing operation, the adhesive being permanently secured to the face of the blank by the pressure applied by the heel compressor. In a preferred manner of practising the invention the adhesive may be applied to the sur-

face of the blank—for example, by blowing it on in powdered form—while the blank is in the compressing mold and immediately before its engagement with the pressure applying die.

From another viewpoint, the invention may be said to reside in the combination, with means for applying a dry adhesive to a face to a heel blank, of means for engaging the said face and pressing the adhesive upon it.

Another feature of the invention consists in the combination with a heel compressor, of means operating automatically to apply dry adhesive to the seat face of a heel blank while the blank is in the mold and before the engagement of the seat die with the said face of the heel.

A further feature of the invention comprises the combination, with the molds of a heel compressing machine of means, operated automatically in timed relation to the molds, to transfer paste to a heel blank in the molds. This may conveniently be effected by operating the paste transferring means from the reciprocating head which carries and operates the molds.

These and other features of the invention, including both details of the method and certain details of construction and combinations of parts of mechanism for carrying it out effectively, will become clearly apparent from reading the following description of one example of the invention, reference being had to the accompanying drawing, in which the figure shows a dry paste applying mechanism in combination with so much of a commercial heel compressing machine as is necessary to explain the invention.

In the foregoing, and in the subjoined detailed description and claims of the invention, the term "heel blank" is used, for convenience, to denote the article being operated upon. It should be understood, however, that it is not necessarily intended to define by this term a completed heel, but that it is intended equally to apply to a heel section or a top lift.

While various agencies may be utilized in practising my method, I prefer, as above indicated, to carry it into effect in connection

with the usual blank molding or compressing operation and, to that end, have combined with the commercial type of heel and top lift compressing mechanism specially suited 5 to the purpose.

The compressing machine may be of the type shown and described in United States Letters Patent, No. 1,172,471, granted Feb. 22, 1916, upon the application of Thomas 10 Lund. In the present drawing, 2 indicates the stationary seat die mounted in the fixed cross head 4. 5, 5 indicate the side pressing dies mounted upon and movable with the vertically reciprocating head 6, and closed 15 as they rise by the inclined links 8, one only of which is shown, having lost motion connections with the fixed cross head 4. The head 6 is actuated by a toggle, one member of which is shown at 9. The ejecting 20 plunger 10 forms the bottom of the mold when a blank is under pressure and has a stem 11 by which it is retained in elevated position when the mold descends to permit the removal of the compressed blank and 25 the introduction of a new blank. As thus far described, the machine is organized and operates as set forth in the patent referred to.

A hopper 15 for dry, powdered adhesive 30 is mounted upon the front of the stationary cross head 4 and has at its lower end a restricted outlet regulated by a gate 16 and terminating in a nozzle 18 which extends obliquely into proximity with the lower face 35 of the seat die 2, and the adjacent face of a heel blank in the mold when the latter approaches the said die. The nozzle may be flexibly mounted to permit it to be displaced upwardly by the mold 5.

40 On the side of the hopper is a cylinder 20 in which is fitted the head 22 of a piston 24 which has a lost motion connection 23 with the vertically reciprocated head 6 of the compressor. In the upper portion of the cylinder 45 20 is fitted a thimble 25 which is spring-pressed downwardly into position to cover a port leading to the nozzle 18. The extent to which the thimble extends below the port, and the tension with which it is held by its 50 spring, is controlled by a rod 26 threaded into the thimble. The rod extends loosely through the top of the cylinder and is threaded into an adjusting nut.

The hopper has a cam track 30 in which 55 runs a lateral extension of a rod 32 carrying a hammer 33 adapted to tap the hopper repeatedly to insure the flow of the powdered paste to the nozzle. The tapping rod extends down to a sleeve 34 guided on the 60 piston rod 24 and movable vertically with and by the mold 5.

In the operation of the machine as equipped and organized as described a heel blank is introduced into the compressor seat 65 face up, resting on the plate 10 as is usual

in the use of the compressor. As the head 6 rises, the molds 5 advance, and just before the heel becomes inclosed between the mold parts 2, and 5, 5 a charge of dry adhesive is automatically discharged from the nozzle 18 on to the seat face of the heel, after which the heel seat die 2 presses the adhesive upon the heel with the powerful pressure exerted for the compression operation. The rise of the head 6 and rod 32 causes the 75 hammer 33 to tap the hopper repeatedly and insure the presence of powder in the nozzle. The rise of the piston 24 effects compression of the air between the piston head 22 and the thimble 25 and, when the piston has 80 risen far enough, its upper end strikes the rod 26 and raises the thimble to uncover the port and allow the air thus compressed to escape into the nozzle and blow the dry adhesive, in the form of a puff or spray, 85 upon the heel. The time of delivery of the adhesive can be regulated with relation to the engagement of the heel with die 2 by adjustment of the rod 26 to cause the discharge to occur earlier or later in the rise 90 of head 6.

Heel blanks thus treated with adhesive may be stored as other heels are commonly stored until brought to the heelng machine where the adhesive can be softened by heat 95 or by touching the coated surface to a wet sponge, or by causing water vapor to come into contact with the seat faces of the blanks before they are applied to the attaching mechanism.

Having explained the nature of this invention, I claim as new and desire to secure by Letters Patent of the United States:—

1. That method of preparing adhesive coated heel blanks which comprises applying 105 a dry adhesive to the surface of a blank and uniting the adhesive to the said surface by pressure.

2. That method of preparing adhesive coated heel blanks which comprises applying 110 a dry adhesive to the surface of a blank and then uniting the adhesive to said surface by the application of pressure.

3. That improvement in the preparation 115 of adhesive coated heel blanks which comprises blowing dry adhesive in powdered form upon a surface of the blank and then applying pressure to the said surface to unite the adhesive thereto.

4. That improvement in the preparation 120 of adhesive coated heel blanks which comprises distributing upon a surface of the blank by compressed air, a measured quantity of dry adhesive in powdered form and thereafter subjecting the blank to compression to force the adhesive into the said surface.

5. That improvement in the preparation 130 of adhesive coated heel blanks which comprises applying a dry adhesive to the sur-

- face of a blank, and then simultaneously pressing the adhesive into said surface and molding the blank. 50
6. The combination with means for applying dry adhesive to a face of a substantially dry heel blank, of means for engaging the said face and pressing the adhesive upon it with sufficient pressure to cause the adhesive to adhere to the blank. 55
- 10 7. The combination with a heel compressing machine, having a mold and a seat die, of automatic means for applying a dry adhesive to the seat face of a blank in the mold prior to the engagement of the blank with said die. 60
- 15 8. In a heel compressor the combination with mold members and a vertically reciprocating head to operate them, of means operated from said head for applying paste to each heel in the molds while the molds are open. 65
- 20 9. In a heel compressor the combination with mold members and a vertically reciprocating head to operate them, of a paste container and means operated from said head to transfer paste to the heels while the mold members are separated. 70
- 25 10. In a heel compressor the combination with mold members and a vertically reciprocating head to operate them, of a dry paste container, an air cylinder and means operated from a moving part of the compressor to effect compression of a charge of air and to cause the air to transfer dry paste from the container to a heel. 75
- 30 11. The combination with molds movable to inclose a heel of means operated automatically in timed relation to the molds to transfer paste to the heel in the molds while the molds are open. 80
- 35 12. The combination with heel compressing means of a hopper, an air cylinder, a piston and means to compress a charge of air and employ it in delivering material from the hopper to the compressing means. 85
- 40 13. The combination with heel compressing means of a piston, a cylinder, a nozzle opening near the compressing means, and means to operate the compressor and the piston in timed relation and cause a charge of air to be discharged through the nozzle. 90
14. The combination with heel compressing means, including a vertically moving head, of a hopper and a connection from said moving head to vibrate the hopper. 55
15. The combination with heel compressing means, of a hopper, a cam track, a hammer, and a connection from said moving head coöperating with the cam track to cause the hammer to tap the hopper. 60
16. The combination with a holder for a heel to be treated, of an air cylinder, a piston, a member in the cylinder arranged to be moved by the piston to open a port leading toward the article, and means to operate the piston. 65
17. The combination with heel compressing means, of a cylinder 20, a piston 22 operated from the compressing means, a thimble 25 movable in the cylinder, said cylinder having a port leading toward the compressing means, a spring holding the thimble over the port, and connections operated by the piston to move the thimble to uncover the port in timed relation to the operation of the compressing means. 70
18. The combination with heel compressing means, of an air cylinder having a port discharging toward the compressing means, a piston, and a lost motion connection between the compressing means and the piston arranged to compress a charge of air and to open the port at a predetermined time in the operation of the compressing means. 80
19. The combination with means constructed and arranged to inclose a heel and then cause engagement of the heel with a seat pressing die, of means for automatically delivering a charge of adhesive in position to be pressed upon the heel by the die. 90
- In testimony whereof I have signed my name to this specification.

THOMAS LUND.
